UNITED STATES PATENT OFFICE

2,608,184

HAIR CLIPPER MACHINE

Hans P. Bergen, Ogden, Utah

Application August 7, 1947, Serial No. 766,955

1 Claim. (Cl. 121—187)

1

This invention relates to hair clippers and has as its primary object the provision of compressed air driven clippers incorporating a reciprocating blade wherein the compressed air enters a channel in the handle or casing of the clippers and acts upon a pivotally mounted piston or lever to oscillate the same back and forth in the chamber.

A further object of the invention is the provision of such clippers provided with an improved valve structure controlling the passage of compressed air into the chamber in which the piston operates and there out of, the valve being rotatably mounted and so constructed that upon rotation thereof air alternately acts upon opposite side faces of the piston and exhaust air is driven from the opposite side of the chamber.

A further object of the invention is the provision of a rotary valve driven by the air motor, and continuously rotated in such manner that the air employed for operating the piston and the air utilized for driving the motor may be provided simultaneously.

A further object of the invention is the provision of a device of this character comprising an improvement upon the sheep clippers shown and disclosed in my copending application entitled "Sheep Clippers," Serial Number 679,741, filed June 27, 1946, now abandoned.

Still other objects reside in the combination of elements, arrangement of parts, and features of construction, all as will be more fully pointed out hereinafter and disclosed in the accompanying drawings wherein there is shown a preferred embodiment of this inventive concept.

In the drawings:

Figure 1 is a top plan view of one form of hair clipper embodying features of the instant invention.

Figure 2 is a side elevational view of the construction shown in Figure 1.

Figure 3 is a sectional view taken substantially along the line 3—3 of the construction shown in Figure 2.

Figure 4 is a sectional view taken substantially along the line 4—4 of Figure 1 as viewed in the direction indicated by the arrows.

Figure 5 is a sectional view taken substantially along the line 5—5 of Figure 3 as viewed in the direction indicated by the arrows.

Figure 6 is a sectional view taken substantially along the line 6—6 of Figure 4 as viewed in the direction indicated by the arrows.

Figure 7 is a sectional view taken substantially along the line 7—7 of Figure 4 as viewed in the direction indicated by the arrows, the rotor of the device being removed.

2

Figure 8 is a sectional view taken substantially along the line 8—8 of Figure 4 as viewed in the direction indicated by the arrows, the rotor being removed.

Figure 9 is a sectional view taken substantially along the line 9—9 of Figure 4 as viewed in the direction indicated by the arrows.

Figure 10 is a top plan view of a constructional detail.

10 Figure 11 is a sectional view taken substantially along the line 11—11 of Figure 10 as viewed in the direction indicated by the arrows.

Similar reference characters refer to similar parts throughout the several views of the drawing.

15 Referring now to the drawings in detail, the instant invention includes a casing or cover 20, provided with a removable top plate 21 adapted to be secured thereto as by screws 22 or the like.

20 The casing 20 includes an offset at one extremity, to which is secured a fixed blade member 23 having a plurality of teeth 24 thereon. The cutting face of the blade 23 is adjacent an open end of the casing 10, which is adapted to have positioned therein a movable cutting blade 25 provided with a plurality of teeth 26 adapted, upon reciprocation of the blade 25 in a manner to be more fully described hereinafter to coact with the teeth 24 to effect the cutting action.

25 30 The fixed blade 25 is provided as best shown in Figure 3 with a slot 27, within which is positioned a movable lever 28, the lever being provided with a pair of inserts 29 and 30 respectively provided at their upper and lower faces

35 with sockets for the accommodation of ball members 31 and 32 respectively. Ball member 31 is resiliently mounted as on a spring 33 secured in a socket 34 in the upper portion of cover 21, affording a relatively resilient connection be-

40 tween the upper portion of member 28 and the top of the casing. Conversely ball member 32 comprises the extremity of a stub 35 fixedly secured as by a locknut 36 in an aperture centrally positioned in the base of the casing.

45 The rear extremity of member 28 terminates in a ball 40, adapted to engage in longitudinally extending socket 41, positioned in the rounded extremity 42 of a piston generally indicated at 43 and to be described more fully hereinafter.

50 Rounded extremity 42 is mounted on a pivot 45, extending entirely through the casing, and secured in position as by a nut 46 engaging a threaded extremity thereof. The piston 45 is carried by a sealing insert 50, extending trans-

versely across the interior of the casing, and de-

fining the outer limit of an interiorly positioned air chamber 51, the purpose of which will be more fully pointed out hereinafter. It may here be noted that a sealing gasket may be interposed between casing 20 and its associated cover 21 in order to maintain the chamber 51 in substantially air tight relation.

Referring now to the piston 43 in detail, it will be seen that the construction comprises an arcuate plate-like member extending from the cylindrical portion 42 outwardly substantially the full extent of the air chamber 51. The plate-like portion is provided with a plurality of channels 55 in its ends and top and bottom, within which are positioned as best shown in Figure 4 lead springs 56 which are adapted to bias sealing strips 57 outwardly into contact with the walls of the air chamber. An additional sealing member 58 of arcuate configuration embraces the connection of the plate like portion with the cylindrical portion, thus forming an effective seal for the slot extending into the supporting member 50.

It will now be seen that the arrangement is such that when air is admitted to the chamber 51 on one side of the piston 43 the same will be moved to the opposite side of the chamber, whereupon admission of air to the opposite side of the chamber will cause a reverse swing exhausting air from the first mentioned side.

Means are provided for effecting such alternate admission of air, and include an arcuate baffle 60 adapted to abut one end of the piston, and provided on opposite sides thereof with air passages 61 and 62.

It is to be noted that the rear portion of casing 20 opposite the blade portion terminates in a relatively cylindrical part 65, to which is adapted to be secured as by screws 66, an end cap 67, which includes a threaded flange 68 adapted to be engaged by a cap like member 69 surrounding and having secured thereto an exhaust tube 70. Concentric with the exhaust tube 70 and interiorly positioned there within is an air inlet 71, which engages a nipple 72, and is threaded into a bore 73, in an interior solid portion 74 of end cap 67. The nipple 73 is hollow and communicates with an air inlet passage 78 provided at its extremity with a bleed valve 79.

Journalized between the inner extremity of the portion 60 and the portion 74 is a rotor generally indicated at 80, revolvable in a cylindrical opening 81, and provided on its external periphery with cups 82, adapted for rotation of the device. As best shown in Figure 9 the rotor includes two semi-circular slotted grooves 83 and 84, extending entirely therethrough, but being concentric and not aligned. The respective journals are indicated at 87 and 88.

The rotary valve 80 is adapted to be rotated by the admission of air from inlet 78 to a passage 90 having an inlet 91 in the base of enlarged portion 65 of casing 20, the air after having served to drive the rotor passing through an exit 92, and thence through a passage 93 into the interior of cup 69 and thence outwardly through outlet tube 70. It will thus be seen that the rotor is continuously rotated while air is admitted through the inlet nipple 73.

The inner face of member 60 as best shown in Figure 7 is provided with two elongated slots, 95 and 96 respectively, in such manner and so aligned that the slots 95 and 96 communicate alternately with the channels 83 and 84 during the rotation of the rotary valve 80 and the

channels 83 and 84 serve as both inlet and outlet in a manner to be described more fully hereinafter. The slot 95 is in communication with the passageway 61, while the front 96 is in communication with the passageway 62 leading into the air chamber 51.

On the opposite side of the rotor the inner face of the member 74 is provided with two inlet openings 97 and 98 and in alignment therewith and positioned on a larger diameter are two outlet openings 99 and 100. The apertures 97 and 98 are both in communication with and comprise the ends of inlets 101 and 102 respectively which are in communication with the air inlet at the extremity of the nipple 73. The outlets 99 and 100 are correspondingly aligned with and comprise the mouths of passageways 103 and 104 which extend through the member 74 into communication with the interior of the cap 69, from which air may pass to the outlet tube 70.

From the foregoing the operation of the device should now be readily understandable. As air is admitted into the passage 78, the turbine rotary valve 80 is rotated by admission of air through the inlet 91 to the cups 82. Such rotation selectively opens one of the inlets 98 or 91, in accordance with the passage of a groove 83 or 84 thereby. Simultaneously the opposite groove opens outlet 99 or 100. Since the channels are at all times in communication through the elongated slots 95 and 96 with the passageways 61 and 62 it will be seen that when passageway 60 serves as an air inlet admitting air to one side of piston 43 air simultaneously will be emitted through passage 62, channel 83, and outlet passageway 104. Obviously, the continued rotation of turbine valve 80 will reverse the action, thus effectively reciprocating the piston 43, which in the manner previously described will effect reciprocation of the movable blade 25, thus effecting the shearing action with the fixed blade 23.

From the foregoing it will now be seen that there is herein provided an improved hair clipper, which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

53. In a fluid motor for a hair clipper having a cylindrical casing having a cylindrical opening therein, an exhaust tube connected to said casing, an air inlet tube concentric with the exhaust tube and interiorly thereof, an air inlet passage 60 communicating with said air inlet tube, a rotor rotatably mounted in the casing and positioned in the cylindrical opening, relatively spaced cups on the periphery of said rotor, a first semi-circular groove extending through said rotor, a second semi-circular groove of greater radius than said first semi-circular groove in said rotor with the ends of the first and second grooves extending toward the center of the rotor in concentric relation to each other with the ends of the first groove inwardly of the ends of the second groove, a passage communicating with said air inlet passage and said cylindrical opening so that air entering said passage will impinge against the cups on the periphery of the rotor, a second passage 65 communicating with the said exhaust tube where-

by the air after it has served to drive the rotor will pass outwardly of said exhaust tube, a pair of elongated slots in said casing aligned with said semi-circular grooves so that said grooves and said slots are in alternate communication with each other, air passages extending from and in communication with each of said slots, a pair of inlet openings in said casing, a pair of outlet openings in said casing radially of and in alignment with said inlet openings, and said inlet openings are in communication with said air inlet tube and said outlet openings are in communication with said air exhaust tube and a piston adapted to be reciprocated by the escape of air through said grooves.

HANS P. BERGEN.
